UNITED STATES PATENT OFFICE.

MARCEL WAGNER, OF MULHOUSE, FRANCE.

ROOFING FASTENING.

Application filed April 22, 1926, Serial No. 103,914, and in France April 28, 1925.

The object of my invention is to provide a device for insuring water-tight attachment of corrugated and smooth roofing (iron plates, cement plates, asbestos plates, etc.) either on metal framework or on timber work or on battens.

The characteristics of said device are set forth in the following description and will be better understood by reference to the accompanying drawings wherein:

Figure 1 is an elevation showing one embodiment of my device adapted for securing corrugated iron plates on iron framings.

Figures 2 and 3 are sectional views of corrugated iron plates secured by means of said device.

Figure 4 illustrates a modification of the device shown by Figure 1.

Figure 5 is an elevation showing an embodiment of my device as adapted for securing sheet metal plates on timber work.

Figure 6 shows corrugated iron plates secured by means of the latter device.

Figures 7, 8 and 9 relate to embodiments of the invention adapted to permit relative movements of the roofing and of the under-roofing caused by expansion and contraction due to temperature variations.

Figure 7 illustrates an embodiment of my device as adapted for securing roofing on timber-work.

Figure 7^a shows a detail thereof.

Figure 8 shows a device adapted for securing roofing on metal framework.

Figure 9 illustrates a device adapted for securing roofing on battens or on any plane surfaces.

Figure 10 shows, partly in section, an implement for positioning the fastener illustrated by Figure 11 which is the same as the one shown by Figure 7 but on an enlarged scale.

Figure 10^a is a cross-section on line 10—10^a of Figure 10.

Figures 12, 13 and 14 relate to a modification applicable preferably where the overlapping of broadly corrugated plates is desired to be reduced as much as possible.

The device shown by Figure 12 is suitable for timber-work, the one shown by Figure 13 for metal framing, and the one shown by Figure 14 comprises an articulation or link analogous to the one shown by Figures 7,

8 and 9 while the attachment thereof can be effected by means of the implement represented in Figure 10.

In all the figures the same reference letters denote the same parts.

The securing or fastening device shown by Figures 1, 2, and 3, is essentially constituted by a metal hook A, preferably made of iron, the top portion B of which is threaded, while its bottom portion C is bent or curved so as to offer a shape fitting the section of the framework beams or girders D (Figures 2 and 3).

On the stem of the hook A is slidably mounted a sleeve F provided at its lower end with a sheet-metal member E shaped to fit the corrugations of the plates K that make up the roofing. Above sleeve F is positioned a square disk G made of malleable metal, preferably of lead, upon which is superimposed a cap H topped in its turn by a washer I, preferably made of lead. A nut J screws on threads B. Optionally an iron washer may be interposed between said nut and washer I.

I use the above described device in the following manner:

Having laid in alignment on the framing the corrugated or smooth plates K (Figures 2 and 3) I mark the fastening points thereon by means of a chalk line, after which I pierce said plates at the proper places through the tops of the corrugations, as usual, taking care that the holes be of a diameter slightly larger than the diameter of hook A in order to allow the roofing sufficient play for expansion and contraction.

I lift up the plates at the points where they overlap and separate the stem of each hook A from all the above described movable parts. I then introduce between the plates the sleeved separating or partition member E—F so that the sleeve thereof will pass through the hole in the upper plate and protrude above the roofing (Figures 2 and 3). I then introduce the stem of the fastening member A into sleeve F, while hooking, by means of portion C, the metal beam or girder D. I then put on the leaden disk G so that its diagonal will be set exactly in the direction of the roof's slope. I next position the closing cap H, the bases of which, preferably square and slightly

convex to conform with the shape of the corrugations, anchors in the leaden plate located below it.

I set the diagonal of said cap base so that it also will be in the direction of the roof's slope. I then cover cap H with leaden washer I, and, if I so desire, with a sheet-metal or an iron washer, and I clamp and lock the whole together by tightening nut J.

Of course, the fastening device for metal framework may be made of the type illustrated by Figure 4. In this case, the hooked rod or bolt is analogous to the aforescribed one and the sheet-iron plates of the roofing are joined by means of two nuts J¹—J² combined with two malleable metal washers I¹, I².

The lower nut J² and its washer I² are for the purpose of preventing the pressure exerted by the upper nut J¹ from exerting harmful action on the corrugations of plates K.

For securing said plates, I first tighten the upper nut J¹ so that said plates will rest truly on the frame work, and, then, I tighten jam-nut or check-nut J².

I will now describe, by reference to Figures 5 and 6, a fastener adapted to secure roofing on timber-work and battens.

In this case, the fastener is formed of a metal rod A¹, threaded at its top portion B¹, and comprising, fixed at X by any suitable means, a convex metal separating or spacing member E¹ analogous to the one shown at E in Figures 1, 2 and 3.

The lower end of rod A¹ is tapered or pointed and provided with barbs or flukes L. A leaden washer I (and, if desired, an iron washer) is superimposed over the sheet-iron member E¹ and a nut J² is screwed on the threaded portion B¹.

This device is used as follows:

Having properly laid the sheet-iron plates and completed their perforation, as hereinbefore explained, I form holes in the rafters or such like so as to facilitate the driving in of rods A¹. I then push back the first row of plates one plate's width, and I secure the first plate by means of rod A¹, proceeding in such a way that member E¹ will rest truly on the corrugation of said plate. Head M of the fastening rod should preferably be rounded or recessed so as to prevent the hammering from damaging the threads.

I then lay the next plate by engaging the latter's holes on the threaded portions of the fastenings. I position the leaden washer I, and if any, the aforementioned iron washer, and I clamp the whole together by means of nut J.

Of course, the devices just described can be applied in the same way as above for securing smooth plates, but, in the latter case, the members E—E¹ should be flat instead of convex.

The above described devices offer numerous advantages, to wit:

In the case of corrugated iron sheets or plates the latter's corrugations are reinforced at the fastening points by the convex separating member positioned between the plates so that the pressure of the nut can no longer have the least detrimental influence. Water, meeting first of all the part of the cap which is lined with lead or other malleable metal, gets, therefore, but very little hold, and is divided by the cap and is immediately led into the troughs of the corrugations. If, however, water eventually manages to find its way under the base of the closing cap and of the leaden disk, it would meet the convex separating member E and its sleeve F which projects through the roofing plates into the closing cap. Such water would then again be led into the troughs of the corrugations and would drip on the corrugated plate next below. Hence the invention constitutes, due to these facts, a hermetic and absolutely water-tight fastening.

Since the convex separating members reinforce the plates, my invention offers a better foothold on corrugated roofings, especially if care is taken to walk as nearly as possible along the lines of fastening points. Furthermore, the fastening devices protrude a good deal, thereby permitting roof-layers to use them as supports for any scaffoldings, ladders, etc., whereby the handling of roofing plates is greatly facilitated.

In the case of roofing to be secured on timber-work or battens the same advantages obtain as to water-tightness, with this difference, however, that any water finding its way under the top washer would meet the member E¹ which is fast on threaded rod A¹.

The fastening rods are provided with barbs which hold them firmly in the timber or wood and they cannot shake themselves loose since they have to carry the weight of the roofing and are thereby kept secure. Indeed, even if they actually become loose, a practical impossibility, no infiltration of water could occur since there would always remain the separating member bolted to the upper plate of the roofing. All the foregoing explanations relating to the fastening or securing of corrugated iron sheets or plates apply also to smooth metal sheets and plates.

It should be noted that, in all cases, the separating members E—E¹ can be made more or less long. The longer they are the more the roofing will be reinforced and the better supported, so that it will become possible to lay said roofing on more widely spaced bearings, which means a substantial saving.

I will now refer to Figures 7 to 11.

The chief characteristic of the device illustrated by those figures is the fact that the securing member proper is made in two parts articulated on one another by any suitable means, said articulation being a "take down" one, if desired.

Another characteristic of said device relates to the peculiar and special construction of the member that serves to lock the component parts of the device on the overlapping surfaces.

The device shown by Figure 7 comprises a metal rod A⁴, having top portion B threaded and its lower portion linked to a tapered rod A⁵ provided, for instance, at its free end with barbs L.

The linking can be effected by means of, say, two eyelets A², A³ or by any other suitable means. As already stated, it can be made disconnectible.

Said articulated rod is combined with: a separating member or partition E fitted at its upper portion with; a square disk G of malleable metal; a suitably shaped iron cap H; a cover Z, made of cast iron or of any other metal and formed internally with a depending hemispherical portion Y provided with a threaded hole X¹. Said piece Z is locked by means of a check nut or jam nut W screwed on the end of rod A⁴ which terminates in a point. A wedge Z¹ (Fig. 7a) may be provided and may be driven through a slot B¹ in the threaded part B of said rod to prevent any loosening of the check nut.

The device illustrated by Figure 8 is intended for securing roofings on metal beams or girders. It only differs from that shown by Figure 7 by the feature that rod A⁴ is provided with a hook A⁶ which is shaped to fit the section of the metal beam.

The device illustrated by Figure 9 is designed for the purpose of securing roofing on battens or plane surfaces and comprises at its lower part a small plate P wherein is an eye A⁷.

Figure 10 shows a tool or implement which is used in applying the articulated fastening device of Figure 7, represented on an enlarged scale at Figure 11.

Said tool is composed of a metal tube T permitting rod A⁴ to be passed through. The upper portion of this tube may be fitted inside with a wooden sheath Q intended to protect the threading B of rod A⁴. In its lower portion, tube T has suitably formed and sized recesses to permit the sliding of eyes A² and A³.

The overlapping plates K are laid on one another, as shown by Figure 7 and are formed with holes at suitable places. Through these holes I run the tool or implement above described, said tool holding the fastening member. I rest the lower end of tube T on the frame work and I strike blows on the free end of rod A⁴ until it is entirely

driven into tube T. I then remove the tool and proceed with the positioning of the various elements constituting the fastening device in the same manner as afore explained.

The modification shown by Figure 12 is adapted for timber-work. It permits, as hereinbefore stated, to spare as much as possible the overlapping of broad-corrugated plates. This device is constituted by a rod A⁸, threaded at its top portion B, which is tapered and terminates at its bottom in barbs L. In the case of metal girders, said barbs may be replaced by a hook A⁹ shaped to fit the girder section.

Said rod may also have an articulation of any kind, as in the case of Figures 7, 8, 10 and 11. In all cases it is combined with a socket or sleeve F² provided with an oval base E² shaped to conform to the section of the corrugation. The outside of said sleeve is threaded. A washer G², made of lead or other malleable metal, an iron washer H² and an outer socket or sleeve I² complete the device. The lower part of socket I² has its inside threaded so as to screw on sleeve F², and its upper part, also threaded on the inside, is adapted to be screwed on rod A⁸.

Said socket I² can be put on by means of a suitable spanner. Its outside may be made with four or six faces so as to be operated like an ordinary square or hexagonal nut.

For laying the roofing plates I proceed as follows:

I perforate said plates at the required places. I then introduce sleeve F² into a hole so made. I screw on the sleeve the leaden washer G² so that the sleeve will be properly held in the plate.

It should be noted that when laying roofing plates on a metal framing the fastening rods should be introduced from below.

If articulated rods are used for laying roofing on timber-work, they should, of course, be first secured on the rafters by means of the contrivance shown by Figure 10.

The above described device will do away with all danger of injury to the plate corrugations either from the pressure of the clamping nut or from careless or excessive driving in of nails or fastening screws. By being screwed on the thread of rod A⁸ the fixing socket I² engages the threads on sleeve F² and, by bearing on iron washer H², draws base E², whereby leaden washer G² can be firmly clamped between the iron washer and the plate so as to form a perfectly watertight joint.

Base E² serves as a support for the plate, and hence prevents the corrugation from sinking, sagging or warping and being damaged in the event of any overload happening to be imposed upon the roofing. The fastening of the plates to the under-roofing is never too strong. My device will also

prevent any infiltration of water that might occur in case rod A⁸ should become loosened from the under-roofing, since the joint of the fastening point of the plate must always remain gripped between socket I² and sleeve F² which are screwed into one another.

Obviously, the latter device can be used not only for broad corrugated but also for ordinary corrugated iron roofing.

Having now particularly ascertained and described the nature of my said invention as well as the manner in which the same is to be performed I declare that what I claim is:

- 15 1. Means for fastening overlapping roofing plates to a supporting framework, comprising a fastening rod which projects upwardly through a perforation in at least one of the overlapping plates and which has its lower end rigidly engaged with the adjacent member of the framework; a rigid strengthening member through which said rod extends having its entire upper face fitting flush against the inner surface of the perforated plate; a malleable metal washer mounted on the projecting portion of the rod and disposed against the external surface of said perforated plate; and a clamping member threaded on said projecting rod portion and anchored in the external surface of said washer.

- 20 2. Means for fastening to a supporting framework roofing plates having interfitting, overlapping corrugations, comprising a fastening rod which projects upwardly through a perforation in at least one corrugation and which has its lower end rigidly engaged with the adjacent member of the framework; a rigid convex strengthening member through which said rod extends having its entire upper face fitting flush against the inner surface of the perforated corrugation; a malleable metal washer mounted on the projecting portion of the rod and disposed against the external surface of said perforated corrugation; and a clamping member threaded on said projecting rod portion and anchored in the external surface of said washer.

- 25 3. Means for fastening overlapping roofing plates to a supporting framework, comprising a fastening rod which projects upwardly through a perforation in at least one of the overlapping plates and which has its lower end driven into the adjacent member of the framework and formed with barbs to prevent its displacement; a strengthening member through which said rod extends having its entire upper face fitting flush

against the inner surface of the perforated plate; a malleable metal washer mounted on the projecting portion of the rod and disposed against the external surface of said perforated plate; and a clamping member threaded on said projecting rod portion and anchored in the external surface of said washer.

4. Means for fastening overlapping roofing plates to a supporting framework, comprising a fastening rod which projects upwardly through alining openings in the outer and inner overlapping portions of the plates and which has its lower end rigidly engaged with the adjacent member of the framework; a rigid strengthening and separating member through which said rod extends interposed between said overlapping plate portions and having its opposite faces fitting flush against the corresponding surfaces of such portions; a malleable metal washer mounted on the projecting portion of the rod and disposed against the external surface of the outer overlapping plate portion; and a clamping member threaded upon said projecting rod portion and anchored in the external surface of the washer.

5. Fastening means, according to claim 4, in which the roofing plates are corrugated and have the corrugations of their overlapping portions interfitted; and in which the strengthening member is of convexo-concave section, is interposed between the interfitting corrugations, and conforms to the curvature thereof.

6. Means for fastening overlapping roofing plates to a supporting framework, comprising a fastening rod which projects upwardly through alining openings in the outer and inner overlapping portions of the plates and which has its lower end driven into the adjacent member of the framework and formed with barbs to prevent its displacement; a strengthening and separating member through which said rod extends interposed between said overlapping plate portions and having its opposite faces fitting flush against the corresponding surfaces of such portions; a malleable metal washer mounted on the projecting portion of the rod and disposed against the external surface of the outer overlapping plate portion; and a clamping member threaded upon said projecting rod portion and anchored in the external surface of the washer.

In testimony whereof I affix my signature.

MARCEL WAGNER.
